DIE-CASTING MACHINE

William Coulthard, Scotby, near Carlisle, England

Application February 23, 1949, Serial No. 77,850
In Great Britain February 11, 1948

2 Claims. (Cl. 22—68)

1

This invention is for improvements in or relating to die-casting, injection moulding and like machines (hereinafter called die-casting machines) of the kind used for the casting or moulding of articles in metal, plastics or like materials.

The invention is concerned with die-casting and like machines of the type comprising a shooting cylinder or combined metal magazine (i. e. a magazine for the molten metal or other material) and shooting cylinder, a ram or plunger working in the cylinder and operating to shoot the molten metal or other material into the dies or mould.

According to the present invention there is provided a die-casting machine of the kind above specified wherein the shooting cylinder or a combined metal magazine and shooting cylinder is supported, or is adapted to be supported, by the die or die-carrying part of the machine in operative position in relation to the dies. In a preferred embodiment of the invention a combined metal magazine and shooting cylinder is supported from the die-parts, die-carriers or bolster-plates thereon by horizontally disposed pins which permit the required opening movement of the movable die-part whilst maintaining or helping to maintain the metal magazine and shooting cylinder in correct position relatively to the dies or mould.

Major advantages of the arrangement according to the present invention are:

(a) The thrust of the metal forcing plunger or ram working in the shooting cylinder is taken by the dies or bolster-plates and is not communicated (at least directly or to any great extent) to the tie rods and machine frame. This means that a lighter frame construction can be adopted for machines designed to deal with aluminium and like materials than has been possible heretofore, or, alternatively, existing machines at present only capable of dealing with materials such as zinc can readily be modified so as to serve for the production of aluminium and like castings requiring the cold chamber method of manufacture.

(b) It is possible to use die-halves or parts of varying and different thicknesses, longer or shorter metal magazine-supporting pins being used according to the varying thicknesses of the dies. In the present type of split-gate, cold-chamber, die-casting machines the fixed half or part of the die has to be of a certain thickness, according to the fixed location of the metal magazine and shooting cylinder on the frame of the

2

machine. The advantage of being able to vary the thickness of the die-parts will be obvious to those skilled in the art of die-casting and the like.

5 The invention is particularly applicable to die-casting machines of the cold-chamber side-shot or under-shot type. In cold-chamber machines the molten metal is generally ladled into the metal magazine or upper part of the shooting cylinder when the dies are open and the metal forcing plunger is retracted. The invention can, however, be applied to other types of die-casting machines provided there is sufficient space to accommodate the device thereon for the purpose of converting them to cold-chamber machines suitable for the production of castings or mouldings requiring a machine of the cold-chamber type.

One embodiment of the invention as applied to 20 a die-casting machine of the cold-chamber type will now be described by way of example with reference to the accompanying semi-diagrammatic drawings. On the drawings:

Figure 1 is a side elevation of the complete 25 machine,

Figure 2 is a cross-sectional view corresponding to line II—II of Fig. 1, the dies being removed to show the bolster-plate for the fixed die-carrier of the machine and also the upper part of the shooting cylinder which is supported from said bolster-plate and die-carrier, the supporting means being in section on the line II—II of Figure 3,

Figure 3 is a side elevation of the bolster-plates, 35 for both the fixed and moving die-carriers, and the shooting cylinder, and

Figure 4 is a side elevation of the two bolster-plates and a sectional elevation of the combined shooting cylinder and metal magazine, the section being through the vertical axis of the cylinder.

The general construction of the machine shown in Figure 1 follows existing practice and comprises a frame 10 supporting a fixed die-carrier 11 and tie rod guides 12 for a movable die-carrier 13. Movement of the movable die-carrier is effected by compressed air through a piston and cylinder device 14 under the control of a hand-operable valve 15.

The combined metal magazine and shooting cylinder is indicated at 16, see Figure 1, and comprises (see Figures 3, 4 and 5) a cylinder proper 17 in which works a piston 18 connected to and operating the shooting ram 19, the latter shooting the molten metal from the metal magazine

20 into the cavities of the mated dies 21 and 22 in the usual way. It will be noted that the metal magazine 20 is supported in the removable plate or cover 23 of the shooting cylinder 17. Movement of the piston 18 and ram 19 in the "shooting" direction is effected by compressed air admitted by a part-flexible pipe 24 and acting on the underside 25 of the piston 18. Return movement of the piston and ram is effected by compressed air at constant pressure supplied by a part-flexible pipe 26 and acting on the annulus 27 of the piston. The compressed air acting on this annulus is only capable of effecting return movement of the piston and ram when the pipe 24 is open to atmosphere. Control of the connection of pipe 24 to the source of compressed air, to effect a "shot" and to atmosphere for return movement of the shooting ram is provided by a hand-operable valve 28.

The combined metal magazine and shooting cylinder, instead of being fixed to or integral with the main frame of the machine as has been the case heretofore, constitutes a separate unit suspended from the die-carriers. This is effected, in the embodiment of the invention shown on the drawings, by providing the cover 23 of the shooting cylinder 17 with lugs 29 having holes 30 to receive pins 31. The heads 32 of the pins 31 (see Figure 3) are trapped in holes 33 in the bolster-plate 34 which is attached to the fixed die-carrier 11 whilst the forward ends of the pins 31 extend freely forward for a sliding fit in bushes 35 in the bolster-plate 36 which is attached to the movable die-carrier 13. It will be understood that the bolster-plates 34 and 36 carry the die-halves 21 and 22 in the usual way. In addition to the pins 31 screws may be provided for securing the lugs of the shooting cylinder cover to the bolster-plate 34. The pins 31 and the holes in the bushes 35 are aligned correctly so that the bushes will "find" the free ends of the pins and slide smoothly over them as the dies are closed. Thus, when the dies are open, the pins 31 are cantilevers as their one ends are supported by the fixed die carrier and the intermediate pin portions support the shooting cylinder 16. However, when the dies are closed, both ends of the pins are supported by the die carriers so that the reactive stress between the dies 21 and 22 and the shooting cylinder 16 is taken by the pins 31 and not transmitted to the tie rods 12 or frame 10.

It will be appreciated that in the arrangement just described the thickness of the die-parts 21 and 22 is not limited by the necessity of having to locate the split-gates of the dies in alignment with a metal magazine and shooting ram or plunger the position of which is fixed. With the arrangement just described it is possible by a selection of supporting pins 31 of approximate length and the use of packing pieces between the cover 23, carrying the metal magazine, and bolster-plates, if necessary, to position the metal

magazine 20 to suit the thickness of the die-parts and the position of the split-gate. The position of the latter depends, of course, on the thickness of the die-parts.

5 I claim:

1. In a die-casting machine of the type where-in the opposed sides of a frame are connected by parallel tie rods, a die carrier fixed on one of the sides of the frame, a cooperative die carrier mounted on the tie rods for movement relative to said fixed die carrier, and a shooting cylinder positioned for loading the dies of said carriers, the combination with said fixed die carrier of cantilever support pins fixed thereto and freely projecting forwardly therefrom towards the movable die carrier, sockets in the movable die carrier for slidably receiving the free ends of said pins when the dies are closed, and apertured lugs on said shooting cylinder and slidably mounted 10 on said pins, whereby the shooting cylinder is removably suspended from said pins in an operative position in relation to the dies and the reactionary forces between the dies and cylinder are exclusively taken by said pins.
2. In a die-casting machine of the type where-in the opposed sides of a frame are connected by parallel tie rods, a die carrier fixed on one of the sides of the frame, a cooperative die carrier mounted on the tie rods for movement relative to said fixed die carrier, and a shooting cylinder positioned for loading the dies of said carriers, the combination with said die carriers of bolster plates removably mounted thereon, cantilever support pins removably inserted through the fixed die carrier bolster plate having heads trapped between said plate and die carrier, said pins freely projecting forwardly from said bolster plate towards the movable die carrier, sockets in the movable die carrier bolster plate for slidably receiving the free ends of said pins when the dies are closed, and apertured lugs on said shooting cylinder and slidably mounted 15 on said pins, whereby the shooting cylinder is removably suspended from said pins in an operative position in relation to the dies and the reactionary forces between the dies and cylinder are exclusively taken by said bolster plates and pins.
3. In a die-casting machine of the type where-in the opposed sides of a frame are connected by parallel tie rods, a die carrier fixed on one of the sides of the frame, a cooperative die carrier mounted on the tie rods for movement relative to said fixed die carrier, and a shooting cylinder positioned for loading the dies of said carriers, the combination with said die carriers of bolster plates removably mounted thereon, cantilever support pins removably inserted through the fixed die carrier bolster plate having heads trapped between said plate and die carrier, said pins freely projecting forwardly from said bolster plate towards the movable die carrier, sockets in the movable die carrier bolster plate for slidably receiving the free ends of said pins when the dies are closed, and apertured lugs on said shooting cylinder and slidably mounted 20 on said pins, whereby the shooting cylinder is removably suspended from said pins in an operative position in relation to the dies and the reactionary forces between the dies and cylinder are exclusively taken by said pins.
4. In a die-casting machine of the type where-in the opposed sides of a frame are connected by parallel tie rods, a die carrier fixed on one of the sides of the frame, a cooperative die carrier mounted on the tie rods for movement relative to said fixed die carrier, and a shooting cylinder positioned for loading the dies of said carriers, the combination with said die carriers of bolster plates removably mounted thereon, cantilever support pins removably inserted through the fixed die carrier bolster plate having heads trapped between said plate and die carrier, said pins freely projecting forwardly from said bolster plate towards the movable die carrier, sockets in the movable die carrier bolster plate for slidably receiving the free ends of said pins when the dies are closed, and apertured lugs on said shooting cylinder and slidably mounted 25 on said pins, whereby the shooting cylinder is removably suspended from said pins in an operative position in relation to the dies and the reactionary forces between the dies and cylinder are exclusively taken by said pins.
5. In a die-casting machine of the type where-in the opposed sides of a frame are connected by parallel tie rods, a die carrier fixed on one of the sides of the frame, a cooperative die carrier mounted on the tie rods for movement relative to said fixed die carrier, and a shooting cylinder positioned for loading the dies of said carriers, the combination with said die carriers of bolster plates removably mounted thereon, cantilever support pins removably inserted through the fixed die carrier bolster plate having heads trapped between said plate and die carrier, said pins freely projecting forwardly from said bolster plate towards the movable die carrier, sockets in the movable die carrier bolster plate for slidably receiving the free ends of said pins when the dies are closed, and apertured lugs on said shooting cylinder and slidably mounted 30 on said pins, whereby the shooting cylinder is removably suspended from said pins in an operative position in relation to the dies and the reactionary forces between the dies and cylinder are exclusively taken by said bolster plates and pins.
6. In a die-casting machine of the type where-in the opposed sides of a frame are connected by parallel tie rods, a die carrier fixed on one of the sides of the frame, a cooperative die carrier mounted on the tie rods for movement relative to said fixed die carrier, and a shooting cylinder positioned for loading the dies of said carriers, the combination with said die carriers of bolster plates removably mounted thereon, cantilever support pins removably inserted through the fixed die carrier bolster plate having heads trapped between said plate and die carrier, said pins freely projecting forwardly from said bolster plate towards the movable die carrier, sockets in the movable die carrier bolster plate for slidably receiving the free ends of said pins when the dies are closed, and apertured lugs on said shooting cylinder and slidably mounted 35 on said pins, whereby the shooting cylinder is removably suspended from said pins in an operative position in relation to the dies and the reactionary forces between the dies and cylinder are exclusively taken by said bolster plates and pins.
7. In a die-casting machine of the type where-in the opposed sides of a frame are connected by parallel tie rods, a die carrier fixed on one of the sides of the frame, a cooperative die carrier mounted on the tie rods for movement relative to said fixed die carrier, and a shooting cylinder positioned for loading the dies of said carriers, the combination with said die carriers of bolster plates removably mounted thereon, cantilever support pins removably inserted through the fixed die carrier bolster plate having heads trapped between said plate and die carrier, said pins freely projecting forwardly from said bolster plate towards the movable die carrier, sockets in the movable die carrier bolster plate for slidably receiving the free ends of said pins when the dies are closed, and apertured lugs on said shooting cylinder and slidably mounted 40 on said pins, whereby the shooting cylinder is removably suspended from said pins in an operative position in relation to the dies and the reactionary forces between the dies and cylinder are exclusively taken by said bolster plates and pins.
8. In a die-casting machine of the type where-in the opposed sides of a frame are connected by parallel tie rods, a die carrier fixed on one of the sides of the frame, a cooperative die carrier mounted on the tie rods for movement relative to said fixed die carrier, and a shooting cylinder positioned for loading the dies of said carriers, the combination with said die carriers of bolster plates removably mounted thereon, cantilever support pins removably inserted through the fixed die carrier bolster plate having heads trapped between said plate and die carrier, said pins freely projecting forwardly from said bolster plate towards the movable die carrier, sockets in the movable die carrier bolster plate for slidably receiving the free ends of said pins when the dies are closed, and apertured lugs on said shooting cylinder and slidably mounted 45 on said pins, whereby the shooting cylinder is removably suspended from said pins in an operative position in relation to the dies and the reactionary forces between the dies and cylinder are exclusively taken by said bolster plates and pins.
